UNITED STATES PATENT OFFICE.

CALEB W. HODGDON, OF BOSTON, MASSACHUSETTS.

LASTING AND PEGGING JACK.

SPECIFICATION forming part of Letters Patent No. 268,019, dated November 28, 1882.

Application filed April 14, 1882. (No model.)

To all whom it may concern:

Be it known that I, CALEB W. HODGDON, of Boston, in the State of Massachusetts, have invented Improvements in Boot and Shoe Lasting and Pegging Jacks, of which the following is a specification.

This invention relates to the jacks in which the last is held while the "upper" is being stretched thereon and secured to the insole; and the invention consists in the construction and combination of the various devices embodied therein, as will be hereinafter, in connection with the accompanying drawings, fully described, and specifically defined in the appended claims.

Figure 1 is a side elevation of a jack which embodies my invention, the base being broken away, (but shown in Fig. 8.) Fig. 2 is a sectional elevation of said jack, taken as viewed from the right in Fig. 1, the sectional parts being taken as on line W, Fig. 1. Fig. 3 is a sectional elevation taken as on line x, Fig. 1, and as viewed from the right therein. Fig. 4 is a detached sectional elevation, showing one of the clamping-blocks and the upper portion of its supporting-standard in elevation and the connecting-coupling in longitudinal section. Fig. 5 is an elevation, showing one of the clamping-block standards jointed, and with a modification in the rotating and elevating devices. Fig. 6 shows a left-hand last in section, as taken through the shank, or on line W, Fig. 1, and the clamping-blocks in elevation. Fig. 7 is a view like Fig. 6, except that the last shown is a "right" instead of a "left." Fig. 8 is a detached elevation taken as viewed from the right in Fig. 1, and showing the lower portion of the machine, which is omitted in said Fig. 1.

In said views, A represents the base of the machine, by which it may be secured to a bench or other suitable support. Said base is surmounted by part a, in which is fitted to be revolved the hand-wheel b, whose hub or center is threaded to serve as the nut of screw C, which latter is secured in or formed as an integral part of bed-plate B, which carries the last-supporting devices to be described, and by rotating said wheel b its coating screw C, the bed B, and its attached parts may be raised or lowered at will. The clamp-holding rails

c c are at their ends united by cross-bars e e, and are connected with and supported by the end braces, g g, and the lateral braces f f f f, all which braces rise from part a of the base A, as shown in Figs. 1, 2, and 8. To prevent rotation of bed B, when being raised or lowered, by the action of wheel b, the guide-pins h h are secured in part a and extend loosely through holes in B, and so hold the same from rotation without impeding its vertical movements. The last D, at its heel, is supported upon standard i, the stem of which enters a hole in the top of the last, as shown in Figs. 1, 2. Said standard is pivoted at l in ears j 65 of bed B, and it is rocked forward by cam-lever k, pivoted at l' in a rearward projection of said standard. A spring, m, seated between bed B and a front projection of the standard, serves to rock the same backward when cam-lever k is released. The toe of the last is supported by standard n, which is pivoted at p to saddle t, which is dovetailed to and is adjustable upon the way v of bed B. (See Fig. 3.) Under the front end of the base of standard n is arranged an adjusting-screw, y, threaded in saddle t, and provided with a hand-wheel, z, by which to actuate it. By means of the sliding saddle t standard n may be adjusted at the required distance from heel-standard i 75 to suit all sizes of lasts; and by means of screw y standard n may be inclined at any desired angle, while cam-lever k serves to seat the toe of the shoe firmly in standard n. The clamping-block standards d are formed with a foot, 85 2, which fits to the rounded head of rails e, and so as to be moved linearly thereon, and also to be rocked outwardly and inwardly to the requisite extent to engage and be disengaged from the shoe. The upper portion of said standards is formed with a screw-thread, upon which is fitted the sleeve 3, so as to be vertically adjusted upon the standard. In the upper end of said sleeves is fitted to revolve freely the stem 4 of bracket 5, in which is pivoted 95 the clamp-block 6, to which is secured the cap-plate 7. Said clamping-standards are arranged in pairs, (in the desired number,) and each pair is compressed upon the shoe by the rod 8, provided with a lever-nut, 9, threaded thereon 100 at one end, and with a cam-lever, 10, pivoted at the other extremity. By actuating nut 9

the blocks 6 may be adjusted at the desired distance apart for the shoe to be lasted, when by actuating cam-lever 10 the pressure is applied to the shoe. A coiled spring, 11, arranged on rod 8 serves to expand or open out the standards when lever 10 is raised.

In Fig. 5 standard *d* is shown as formed in two sections, jointed together and secured by a pivot-bolt, 12, provided with a clamping thumb-nut by which to lock the parts in position. By means of such jointing the clamping-blocks 6 and their cap-plates may be adjusted to any incline in the top lines of the shoe. In said Fig. 5 the shank of bracket 5 is shown as threaded in a socket formed upon standard *d*, by which means it may be raised or lowered or the block reversed relatively to the shoe; but such modification is deemed inferior to that before described.

20. In Figs. 6 and 7 the clamping-blocks 6 are shown as formed upon one side to fit the outer curve of the last at the shank thereof, and with the other side formed to fit the inner curve of the last. Thus in Fig. 6 (a left-hand last) the left-hand block is shown as bearing upon the inner curve of the last, while in Fig. 7 the same block is shown as reversed and bearing upon the outer curve of the last; and my invention in this behalf presents the advantage that by having blocks 6 formed upon opposite sides to fit opposite sides of the last at the shank, and also arranged to be reversed by rotation, as described, the same pair of blocks serve when lasting either right or left shoes.

35. I claim as my invention—

1. In a shoe-jack, the combination of base *A*, formed or provided with part *a*, the wheel-nut *b*, seated in part *a*, screw *C*, actuated by said nut, and the last-supporting bed *B*, with its attached devices, carried by said screw and provided with means to secure it from rotation, substantially as specified.

2. The combination of base *A*, the last-supporting bed *B*, with means for vertically adjusting the same relatively to said base, and the clamp-supporting bars *c*, supported by base *A*, with the clamps arranged upon and supported by said bars, substantially as specified.

45. 3. In a shoe-jack, the combination of bars *c*, having a head whose transverse or circumferential outline is an arc exceeding a half-circle, and the clamping-standards *d*, having a foot, 2, formed with a correspondingly curved passage exceeding a half-circle, but of less extent than the curved line of said rails, whereby said standards can only be connected with or

disconnected from said rails at the end thereof, but can be moved thereon to any desired point, and can be vibrated toward or from last *D*, 60 substantially as specified.

4. The combination of standards *d* and clamping-blocks 6, vertically adjustable and pivotally mounted in said standards, substantially as specified. 65

5. The combination of standards *d*, sleeve 3, threaded thereon, and the clamping-blocks pivoted in said sleeves, substantially as specified.

6. The combination of clamping-blocks 6 70 and bracket 5, pivotally united whereby said blocks are rendered self-adjusting relatively to the shoe, substantially as specified.

7. The combination of clamping-block 6, 75 pivotally mounted in and supported by bracket 5, the said bracket provided with its supporting-stem 4, and standard *d*, formed to receive said stem and pivotally support the bracket thereby, substantially as specified.

8. The supporting-standards *d*, formed with 80 an upper and lower section, jointed together and provided with a pivotal clamping-bolt, 12, whereby the upper section of said standards may be vibrated on its pivot parallel with last *D*, to conform block 6 with the top line of said 85 last, substantially as specified.

9. The pivoted reversible clamping-blocks 6, formed upon one side with a curve conforming to the outer curve of the last-shank, and upon the opposite side with a curve of greater 90 radius, to conform to the inner curve of the last-shank, substantially as specified.

10. In combination with clamping-standards *d* *d*, the rod 8, its adjusting-nut 9, and pivoted cam-lever 10, all substantially as specified. 95

11. In combination with standards *d* *d* and rod 8, with means for actuating the same, the helical spring 11, mounted upon said rod, to force apart said standards by its expansive force when released, substantially as specified. 100

12. In combination with the standard *n*, the saddle *t*, pivotally united to said standard, and dovetailed or interlocked with and linearly adjustable upon bed *B*, and adjusting-screw *y*, with means for actuating it, substantially as 105 specified.

13. In combination with bed *B*, the standard *i*, formed to engage last *D*, and pivoted to said bed, and the cam-lever *k*, and reacting spring *m*, all substantially as specified.

CALEB W. HODGDON.
